UNITED STATES PATENT OFFICE.

ISAAC SLAPO, OF NEW YORK, N. Y.

ASH-SIFTER FOR BAKERS' OVENS.

1,168,913.

specification of Letters Patent. Patented Jan. 18, 1916.

Application filed May 13, 1915. Serial No. 27,957.

To all whom it may concern:

Be it known that I, ISAAC SLAPO, a subject of the Czar of Russia, residing at New York city, Manhattan borough, county and State of New York, have invented certain new and useful Improvements in Ash-Sifters for Bakers' Ovens, of which the following is a full, clear, and exact description.

This invention relates to improvements in bakers' ovens, but relates more particularly to a sifting device which is located in the ash-pit under the grate.

One of the objects of my invention is to provide an effectively-operating sifting device arranged so that it can be manipulated to permit a person to get into the oven through the ash-pit and up through the grate frame, the grate being arranged for removal from its frame.

Other features of improvement will hereinafter appear.

I will now proceed to describe my invention in detail, the essential features of which will be summarized in the appended claims, reference being had to the accompanying drawings, forming part hereof, wherein—

Figure 1 is a sectional top plan view of an oven provided with my improvement; Fig. 2 is an enlarged vertical sectional view, the section being taken on a line 2—2 in Fig. 3; Fig. 3 is a longitudinal sectional view, the section being taken on a line 3—3 in Fig. 2; Fig. 4 is a top plan view of the sifter, a portion of the front wall of the oven being shown in section, the other walls being omitted; Fig. 5 is an enlarged sectional detail view, the section being taken on a line 5—5 in Fig. 4, the wall being omitted; and Fig. 6 is a similar view, the section being taken on a line 6—6 in Fig. 3.

In the drawings, 1 indicates a baker's oven provided with a damper 2, consisting of a casing 3 and slidable gate 4 operated by a rod 5 from the front of the oven.

To coöperate with my improved ash-sifter, I provide the oven with a removable grate 5', rotatably supported at 6 by a frame 7, which is preferably water-jacketed. Under the grate 5' is located an ash-pit 8 within which I place my improved sifter 9. The function of the sifter 9 is to receive the ashes from the grate, when said grate is turned, and to separate the dust, etc., from the unconsumed fuel.

My improved sifter comprises a frame 10

consisting of side members 10^a and a front member or cross-bar 11, integral with the side members. One end of the frame 10 is hinged to a tie-bar 12 consisting of the rods 13 and 14, one of which is provided with right hand threads, the other with left hand threads, the rods 13 and 14 being connected by a turnbuckle 15. The tie-bar 12 serves to brace the side walls 16 and 17 of the ash-pit as well as to support the frame 10.

The sifter 9 consists of a plurality of frames or grids 18 and 19, both of which rest upon the frame 10, the grid 18 overlapping and being arranged to slide over the grid 19. The frame members 10^a are offset at 20, the grid 19 resting in the lower portion of the frame 10.

During the sifting operation, the grid 18 is moved to and fro longitudinally of the frame 10 and grid 19. In combination with the longitudinal movement of the grid 18, the frame 10 has imparted thereto a swinging movement in a vertical plane. To accomplish this compound movement, I provide levers 21, pivoted at 22 to the front wall of the oven, the said levers being connected by a rod 23 at their upper ends. Each lever 21 carries an arm 24 and an arm 25, the arm 24 being pivotally connected, by links 26, to the grid 18. The free end of each arm 25 carries a grooved roller 27 contacting with the frame 10; in fact, the arms 25 support the free end of the frame 10. When the levers 21 are swung outwardly, at their upper end, the grid 18 will be moved forwardly and the free end of the frame 10 upwardly, the said movements being dependent upon the extent of movement of the levers 21. The aforesaid movement will effectually sift the ashes.

Should it become necessary for a person to enter a baker's oven, provided with my improvements, the levers 21 will be moved outwardly sufficiently to cause the grids to assume the position shown by dotted lines 28 in Fig. 2; or, in other words, to cause the frame and grids to assume a horizontal position. When the grid 18 is drawn ahead to its full extent so as to be superposed over the lower fixed grid 19, a person can pass upwardly between the frame members 10^a, 10^a and push the grate 5 out of its frame 7, after which the person can pass through the opening now provided and enter the oven proper.

The grid 18 carries guides 29 to slidably receive the frame members 10^a. The grid 19 carries jaws 30 to engage the bar 11 of the frame 10 (Fig. 5). The grid 19 is further provided with flanges 31 to assist in guiding the grid 18 while the grid is being reciprocated. Under normal conditions, the grids 18 and 19 are extended so as to approximately cover the space between the frame-members 10^a as shown in Fig. 4, the grid 18 being arranged to be moved to a superposed position over the grid 19 to provide a space for a person to pass through.

When the movable grid is drawn ahead to its full extent, so as to become superposed over the fixed grid, a space will be provided between the tie-bar 12 and the adjacent end of the drawn ahead grid, which space will be large enough for the passage of a person as before stated. Under normal conditions, the movable grid will occupy that part of the frame between the fixed grid and tie-bar, as shown in Fig. 4; therefore a person could not pass upwardly between the frame members 10^a 10^a, but when the movable grid is drawn ahead to its full extent, there will exist a greater distance between the tie-bar 12 and adjacent end of the movable grid; hence the space referred to.

Having now described my invention, what I claim and desire to secure by Letters Patent is:

1. A sifting device consisting of a plurality of grids arranged in horizontal planes one above the other, a hinged frame therefor, the upper grid being movably mounted on said frame, the lower grid being held against movement upon said frame, means to slide said movable grid over said fixed grid, and means to rock said frame upon its hinged support simultaneously with the movement of said movable grid.

2. A sifting device consisting of a plurality of grids arranged in horizontal planes one above the other, a frame therefor, said frame being hinged at one end thereof, a rocking lever to support said frame at its free end, whereby said frame is swung upon

its hinged support when said lever is rocked, the upper of said grids being slidably mounted on said frame, the lower grid being fixed to said frame, and means connecting the rocking lever and the movable grid. 50

3. A sifting device consisting of a frame hinged at one end to a support, a plurality of grids carried by said frame, the lower grid being fixed to said frame, the upper grid being slidably mounted on said frame and arranged to slide over the fixed grid, a rocking lever pivotally supported adjacent the free end of said frame, an arm carried by said lever, a roller carried by said arm arranged to engage said frame, and a link pivotally secured at one end thereof to said lever and at the other end to said movable grid. 55

4. A sifting device comprising a frame consisting of a plurality of members offset intermediate the ends thereof, a grid fixed to said frame and resting upon the offset portions of said frame members, a grid slidably mounted upon the other portion of said frame members and arranged to slide over the fixed grid, a rocking lever pivotally supported adjacent the free end of said frame, 70 an arm carried by said lever, a roller carried by said arm arranged to engage said frame, and a link pivotally secured at one end thereof to said lever and at the other end to said movable grid. 75

5. A sifter comprising a frame, hinged at one end to a support, a grid slidably mounted on the hinged frame, means to impart to the slideable grid a longitudinal movement, and means to impart to the frame, simultaneously with the longitudinal movement of the grid, a swinging movement in a vertical plane. 85

Signed at New York city, N. Y. this 11 day of May, 1915.

ISAAC X SLAPO.
